UNITED STATES PATENT OFFICE.

SAMUEL L. DENNIS, OF NORFOLK, VIRGINIA.

WINDOW FRAME.

Application filed April 9, 1925. Serial No. 21,941.

To all whom it may concern:

Be it known that I, SAMUEL L. DENNIS, a citizen of the United States of America, and a resident of Norfolk, county of Norfolk, and State of Virginia, have invented 5 certain new and useful Improvements in Window Frames, of which the following is a full and clear specification.

The object of this invention is to provide 10 a simple weather-strip for preventing the ingress of moisture between the outside window-casing-strip and the adjacent face of the building-wall, as more fully hereinafter set forth.

15 In the drawing—

Fig. 1 is a horizontal sectional view of a portion of a window showing my device applied thereto;

20 Fig. 2 is a horizontal section through a portion of the casing-strip showing my weather-strip applied thereto;

Fig. 3 is a perspective view of the casing-strip shown in Fig. 2.

25 Referring to the drawing annexed by reference-characters, 5 designates the usual outside casing-strip of a wooden window-frame. In the inner corner of the outer edge of this casing-strip is formed a kerf, extending diagonally into the strip; into this kerf is 30 fitted a flat bendable strip of sheet-metal 6. This strip of sheet-metal runs the full length of the casing-strip and has about one-third of its width anchored in the strip; and the projecting part of the strip lies at an oblique 35 angle to the inner face of the casing-strip and also the edge face of the strip.

With a flexible weather-strip of this character, it will be seen that when the window-casing is placed in the building, the free 40 edge of the strip will bend down to a position parallel with the face of the usual storm-sheathing 7 and lie flat against the same. The usual finishing-lumber 8 (whether in the form of boards or shingles) 45 abuts against the adjacent edge of the casing-strip and overlies the projecting part of

the weather-strip 6. When the window-casing and the finishing-lumber are thus fastened in position, an effectual weather-proof joint is provided, rendering it practically 50 impossible for moisture to enter the window-casing along this joint. It will be understood that the metal sheet is of such nature that the mere placing of the window-frame in position will bend the free edge of 55 the strip into position to flatten out against the storm-sheathing; that is to say, it will not require any bending or hammering by means of tools, but will flatten into position by the mere placing of the window-frame 60 in position in the building, so that a window-frame having my weather-strip applied thereto can be erected with the same speed that one can that is not provided with it. By having the strip project diagonally from 65 the inner corner or edge of the casing-strip, it will be in position to flatten out by merely shoving the window-casing into place. It is desirable to make the kerf a little distance back from the corner or edge, as shown 70 more plainly in Fig. 2, in order that when the free edge of the metal sheet is bent into position, it will bend against a substantial corner and not a thin edge, as would be the case if the kerf were made directly in the 75 corner edge.

What I claim as new is:

A window-casing weather-strip consisting of a bendable strip of sheet metal having one of its longitudinal edges anchored in a 80 kerf formed in the outside casing-strip of the window-frame, said kerf being located at the inner corner of the outer edge of the casing-strip so that the free portion of the strip will project obliquely beyond the edge 85 of the casing-strip so as to flatten out against the storm-sheathing when the frame is positioned in the building and be covered by the finishing lumber.

In testimony whereof I hereunto affix my 90 signature.

SAMUEL L. DENNIS.
